UNITED STATES PATENT OFFICE.

JOHN ELLIOTT JENKINS, OF CHICAGO, ILLINOIS.

RHEOSTAT.

Application filed March 15, 1922. Serial No. 543,859.

This invention relates to improvements in rheostats, and more particularly to electrical devices for regulating the flow of electric current by the introduction of resistance in a circuit.

The object of the present invention is to provide a new and novel structure for a rheostat, especially designed and constructed for use in radio apparatus, although capable 10 of use wherever the flow of electric current is to be accurately controlled. For instance, in radio apparatus, the transmission of wireless intelligence waves required a close regulation and accurate manipulation of the 15 rheostats of the sending and receiving sets, in order to secure the synchronism of wavelength that is essential to perfect transmission.

The rheostat of the present invention involves those features of construction which 20 will permit of a gradual increase or decrease of the resistance, thus making it possible to obtain very minute variations throughout a considerable range of electrical activity.

25 In the drawing is illustrated a preferred embodiment of the invention, in which—

Figure 1 is a view in front elevation of the rheostat,

30 Figure 2 is a view in side elevation of the rheostat,

Figure 3 is a view in vertical section, as taken on line 3—3 of Figure 1,

35 Figure 4 is an enlarged view showing more clearly the construction of the threaded block, resistance element and contact member, and

40 Figure 5 is a view in front elevation showing the application of an indicating device for indicating the resistance in circuit in every position of the contact member.

The rheostat is ordinarily mounted within 45 convenient reach of the operator of the particular electrical apparatus of which it forms a part, being herein shown as supported upon an upright panel 1. Electrically, it is connected in series with a battery or other source of current supply, and the particular elements into which the current flows. In general, the rheostat comprises a cylindric 50 block 2 made of non-conductive substance, such as hard rubber, condensite, or the like, said block being mounted in any suitable manner, as, for instance, upon the rear face of the panel 1 by means of a screw passing through the block, and anchored in said panel. Cut or otherwise formed in the pe-

riphery or annular face of the block 2 are helical threads 2^a extending transversely from the rear to the front side of the block, and forming between them similarly shaped 60 grooves. These threads are preferably of the V-form of screw thread, although in the present disclosure a left hand thread is used; that is to say, the thread commences adjacent the rear side of the block, traversing the 65 face of the block toward the front side, and describing a true helix around the face thereon. The use of the left handed thread rather than the right handed thread will be explained more in detail in connection with 70 the operation of the rheostat.

Anchored to the front face of the block 2 are two radially disposed conductor plates 3 and 4, which are insulated from each other and arranged in diametrical alignment on 75 opposite sides of the central axis of the block. The ends of the conductor bars terminate beyond the threaded periphery of the block in rearwardly bent fingers 3^a and 4^a respectively, there being mounted in said 80 fingers terminal screws 5—5 whereby the terminal ends of the conductors 6—6^a are attached. As clearly shown in Figure 1, the uppermost arm 3 terminates short of the central axis of the block 2, and is anchored 85 thereto by means of a screw 7, whereas the lowermost arm 4 terminates in a rounded inner extremity surrounding the central portion of the block, and provided with an annular opening 8 concentric with the axis, 90 said end portion being further bifurcated by the provision of a longitudinal slot 9 extending inwardly from the end beyond the annular opening 8. Another screw 10 secures the lower plate 4 to the front side of 95 the block 2.

Extending centrally and axially through the block 2 is a bore into which is fitted a metal bushing or sleeve 11 terminating adjacent the front side of the block in spaced 100 relation with the conductor arm 4, the purpose being that there shall be no direct electrical connection therebetween. Journalled in the bushing 11 is a rotative spindle 12 which projects outwardly from each side of 105 said block, and carries at its forward end a thumb wheel or knob 13, the same being located, as clearly shown in Figure 2, on the opposite side of the panel 1 from the block 2. The knob 13 is preferably made of 110 a suitable insulating material, and is provided with a cylindric extension 13^a of re-

duced diameter, extending toward the block 2, and in the position shown in Figure 2, its end surface is spaced a short distance from the face of the panel 1. At the extreme opposite end of the spindle 12, and adjacent the back side of the block 2, is mounted a fixed collar 14, forming a support or hub for a radial contact arm 15 extending a short distance beyond the periphery of the block 2, and terminating in a transversely bent arm 15^a extending toward, and in parallel relation with the face of said block. Pivotal connected to the transverse end portion 15^a of the arm 15 is a contact finger 16 extending 15 in a general direction at right angles to the arm 15, and circumferentially of the block. A hinge pin 17 connects the arm and finger, the parts thus connected providing an articulated contact member. This finger is furthermore curved slightly to conform with the curvature of the block, and terminates at its free end in an inturned V-shaped point 16^a, adapted to engage the helical groove of the block. It is obvious from the foregoing 25 description and from the drawings, that the spindle 12 is capable of being rotated by the operator through the medium of the knob 13, thus carrying the arm 15 in a circular path with the V-shaped contact point 16 30 engaging the helical grooves cut in the angular face of the block in the manner clearly shown in Figure 4, said finger 16, by reason of its pivotal connection with the arm 15, being free to swing about the axis of the pivot pin 17 as its point 16^a traverses the block in the rotation of the contact arm in either direction.

Lying within the V-shaped grooves 2^a is the resistance element of the device, consisting of a single length of wire 18 which is transformed into the form of a coil by wrapping it around the block, following the helical groove or path. One extremity of the resistance element 18 is anchored in the block 45 at a point adjacent to its rear side thereof by means of a suitable anchor or plug 19, and forms the dead end thereof. The other extremity is similarly anchored immediately adjacent the front side of the block, and in close proximity to the conductor arm 3, said 50 last mentioned end of the resistance element being anchored in the block by means of a plug 20, which in turn is electrically connected to said arm 3 by means of a short conductor 21. As clearly shown in Figure 4, the pointed end of the contact finger 16 has sliding contact with and along the wire 18, as the contact member is rotated in either direction, and said finger tracks or follows 55 in the groove.

The spindle 12 is also constructed so as to have a limited degree of endwise motion, the purpose being to permit said spindle to be utilized as a switch for making and breaking the circuit through the rheostat. The

circuit making and breaking elements will be understood from the following description: Substantially midway between the ends of the spindle 12 is provided a tapered portion 22 of reduced diameter having the 70 general shape of a frustrated cone with its apex toward the outer end of the spindle. The beveled portion 22 is located in close proximity to the opening 8 in the lower conductor plate 4, so that if the spindle is 75 shifted inwardly by pressing on the knob 13, the reduced portion is advanced into said opening with the result that the contact is broken between spindle and plate, thus interrupting the current flow from the plate to 80 the contact arm through the spindle. However, pulling the knob outwardly shifts the spindle 12 endwise, so that the base of the reduced portion again contacts with the plate 4, thereby making contact between plate and 85 spindle. The function of the spindle 12 as a switch member will be clearly understood from the description of the function of the rheostat, which now follows: It may be assumed, for convenience, that the current 90 passes into the rheostat through the conductor 6^a connected with the outer terminal of the plate 4. If the spindle 12 is pulled out so that contact is made through said plate 4 in the manner above described, the 95 path of the current will follow the spindle rearwardly to the arm 15, thence to the resistance element 18 through the contact point 16^a of the arm 16. Passing through the resistance element, the current is conducted to the upper arm 3 through the short conductor 21, thence leaving the rheostat 100 through the conductor 6.

An added feature forming a useful part of the rheostat is an indicating device shown 105 in Figure 5, and consisting of a scale 23 mounted upon the upper portion of the block, or in case the block is secured to a panel, upon the front face of said panel above the knob 13. The scale is preferably curvilinear, having a series of graduations or unit divisions 23^a marked on its face, and arranged in the arc of a circle. Intermediate the scale 23 and the spindle 12, is mounted a rotative tooth disc 24 having a radial pointer 25 projecting from its periphery. The disc meshes with a small pinion 26 fixed to the spindle 12. It follows 115 that the rotation of the spindle is transmitted to the disc 24, but at a reduced angular displacement, thus the pointer acts to indicate upon the scale, the corresponding position of the contact arm with reference to the resistance element 18. The scale may 120 may be calibrated for any desired unit of electrical measurement. Manifestly, the arrangement of the indicating mechanism may be varied, and hence the intention is to show one that would be suitable for the purpose 125 that it is intended.

It is a well known electrical fact that the greater amount of resistance in a circuit, the less current will be delivered to the point of use. It follows, therefore, that the greater the length of the resistance element in circuit, the greater will be the resistance offered thereby. Hence, if it is desired to decrease the amount of current flowing through the circuit, the operator of the particular apparatus with which the rheostat is being used, would rotate the knob 13 in a counterclockwise direction, with the result that the finger 16 would follow the groove around the periphery of the block 2, the said finger at the same time being swung rearwardly toward the rear face of the block. Manifestly, with each rotation of the arm by the block, a turn of the resistance element is added to the circuit, so that when the limit of rotative movement in a counterclockwise direction is reached, the entire resistance element is thrown into circuit, and therefore the current delivered at the point of use is reduced to a minimum. Similarly, if the knob is turned in a clockwise direction, the length of the resistance unit is decreased, and therefore more and more resistance is cut out of the circuit, allowing more current to flow, and to be ultimately delivered to the point of use. Inasmuch as it is customary practice to rotate the thumb wheel to the right for the purpose of increasing the current flow, and to the left to decrease the current flow, the threads of the block are therefore cut left handed.

In wireless receiving apparatus, for instance, the rheostat is manipulated in the manner indicated in order to synchronize the instrument to the particular wave length that the operator wishes to receive. Hence, by increasing or decreasing the resistance, this synchronism of wave lengths is established. By the use of a rheostat in which the contact member has sliding contact along the resistance element, and the path of contact coincides with the path of the current, very minute adjustments can be obtained, and the increase and decrease of resistance accomplished very gradually, and without abrupt fluctuations, which, as in the radio-phone apparatus, is very audible and distracting when magnified through the head phones.

The introduction of a switch as an element of the rheostat permits the device to perform a double function with the manipulation of a single manually operated element; namely, a thumb wheel. In this way the operation of the apparatus is greatly simplified, and the expense and cost of parts materially minimized.

Having described the structure of the device, its function and advantages, I claim as my invention:

1. A rheostat comprising a cylindric block

of non-conductive material, having a helical groove cut in the face thereof, a resistance element consisting of a length of wire surrounding said block and lying within said groove, a contact member extending circumferentially with respect to the face of said block, and engaging at its free end within the groove, and in electrical contact with said resistance element, and means for imparting rotation to said contact member. 75

2. A rheostat comprising a cylindric block of non-conductive material adapted to be mounted in fixed position, and provided with V-threads formed in the annular face thereof, a resistance element lying in and following the grooves formed by said thread, and a rotative contact member adapted to follow said grooves in contact with said resistance element, and to traverse the annular face of said block in the rotation of said contact member about said block. 80

3. A rheostat comprising a cylindric block of non-conductive material adapted to be mounted in fixed position, and provided with V-threads formed in the annular face thereof, a resistance element lying in and following the grooves formed by said thread, and a rotative contact member comprising an articulated arm having a contact point adapted to track within said groove 90 in contact with said resistance element, and to traverse the face of said block in the rotation of said contact member. 95

4. A rheostat comprising a cylindric block of non-conductive material having a helical groove formed in the annular face thereof, a resistance wire lying within said groove, a rotative spindle arranged axially of said block, a radial arm mounted on said spindle, and terminating adjacent the periphery of said block, and a contact finger pivotally connected with said arm, its free end tracking within said groove in contact with said resistance wire, and a knob at one end of said spindle for manually rotating the same. 100 105 110

5. A rheostat comprising a cylindric block of non-conductive material having a helical groove formed in the annular face thereof, a resistance wire lying within said groove, a rotative spindle arranged axially of said block, an arm fixed to one end of said spindle 115 and extending radially of said block and bent transversely at its end, parallel to the face of said block, a finger pivotally connected to said transverse portion of the arm, and arranged circumferentially of said block, the free end of said finger tracking in said groove in contact with said resistance wire, and a knob at the other end of said spindle. 120 125

6. A rheostat comprising a cylindric block of non-conductive material, and having a helical groove formed in the annular face thereof, a resistance wire lying in said groove, a spindle journalled axially of said 130

- block, a radial arm mounted on said spindle adjacent said block, a contact finger pivotally connected with said arm, and adapted to track in said groove in contact with said wire, conductor plates mounted upon said block, one connected with one end of said wire, and the other being apertured to engage said spindle, and a knob for manually rotating said spindle.
10. A rheostat comprising a block of non-conductive material having a helical groove formed in the annular face thereof, a resistance wire lying within said groove, an endwise shifttable and rotative spindle journaled axially in said block, a radial contact arm mounted on said spindle, and adapted to track in said groove in contact with said wire, a conductor connected with one end of said resistance wire, a conductor plate fixed to one side of said block, and adapted for contact with said spindle in one position of endwise movement thereof, said spindle having a reduced portion adjacent said plate, whereby the shifting of said spindle into another position breaks the contact between said spindle and plate.
15. A rheostat comprising a block of non-conductive material, having a helical groove formed in the annular face thereof, a resistance wire lying within said groove, an endwise shifttable and rotative spindle journaled axially in said block, a contact arm mounted on said spindle, and adapted to track in said groove in contact with said wire, a knob mounted at one end of said spindle, a conductor connected with one end of said resistance wire, a conductor plate fixed to one side of said block, and having an apertured end portion adapted in one position of endwise movement of said spindle to have electrical contact therewith, said spindle having a reduced portion adjacent said point of contact, whereby the shifting of said spindle into another position separates said spindle and plate, breaking the circuit therethrough.
20. A rheostat comprising a block of non-conductive material having a helical groove formed in the annular face thereof, a resistance wire lying within said groove, a spindle journaled in said block and capable of limited endwise movement, a radial contact arm mounted in said shaft, and having contact with said wire, a conductor connected with one end of said wire, a conductor plate secured to one side of said block, and provided with a bifurcated end portion adapted for contact with a cylindric portion of said spindle, and a reduced portion adjacent said plate engaging portion, and coacting with said plate to break the circuit through said spindle when the latter is shifted endwise to bring said reduced portion into the plane of said plate.
25. A rheostat comprising a cylindric block having a helical groove formed in the surface thereof, a resistance wire lying within said groove and having one end thereof connected with one terminal of the rheostat, a spindle journaled in said block, and adapted for limited endwise movement, an articulated contact member mounted on said spindle adapted to follow said groove in contact with said wire, and to traverse the annular face of said block in the rotation of said spindle, and a plate forming another terminal and adapted for make and break contact with said spindle in the endwise shifting of the latter.
30. A rheostat comprising a cylindric block of non-conductive material, having a helical groove formed in its annular face, a resistance element lying in said groove, a rotative spindle journaled in said block provided with a contact arm engaging said groove in contact with said resistance element, a fixed scale mounted on said block, a pointer journaled on said block adjacent said scale, and intermediate driving and reducing gears connecting said spindle and pointer.
35. A rheostat comprising a cylindric block of non-conductive material having a helical groove formed in its annular face, a resistance element lying in said groove, a rotative spindle journaled in said block provided with a contact arm engaging said groove in contact with said resistance element, a fixed scale, a toothed disc journaled on said block intermediate said scale and spindle, and provided with a pointer adapted to register with said scale, and a toothed pinion mounted on said spindle and meshing with said disc.
40. In apparatus of the class described, a drum having a resistance wire wound helically thereon, a spindle mounted axially of the drum, a contact operable by rotation of the spindle and tracking along the wire, a terminal connected to one end of the wire, another terminal associated with the spindle all so constructed and arranged that the terminals may be electrically connected or disconnected by a longitudinal movement of the spindle along its axis.
45. In apparatus of the class described, a drum of non-conducting material having a V shaped helical groove therein; a fine wire lying in the bottom of said groove, a pointed contact resting on said wire in said groove, a means for tracking the contact along the wire, and circuit connections to one end of the wire and the contact.
50. In apparatus of the class described, a drum of non-conducting material having a V shaped helical groove therein, a fine wire lying at the bottom of the groove, a resilient pointed contact finger yieldingly pressed against the wire, and control means for tracking the contact finger back and forth

- along the wire by turning the control means.
16. In apparatus of the class described, and in combination, a drum, a resistance wire coiled helically upon the drum, a shaft mounted for revolution axially of the drum, an arm on the shaft, a contact finger movably mounted on the arm, and adapted to track along the wire, means for manually turning the shaft, said turning means and arm being on opposite sides of the drum.
17. In apparatus of the class described, and in combination, a panel, a drum having a flat end secured to the rear face of the panel, a resistance wire, helically wound upon the drum, a shaft revolvably mounted in the drum and passing through the panel, a control knob on the shaft in front of the panel, an arm at the opposite end of the shaft, a contact finger on the arm adapted to track along the wire.
18. A rheostat of the class described comprising a drum provided on its outer cylindrical surface with a helical groove, a resistance wire tautly wound helically around said drum and disposed in said groove, a shaft disposed with its axis concentric with the axis of said drum, said shaft being capable of both rotary and axial movement with respect to said drum, and a contact device carried by said shaft, said contact device being adapted to move both around and longitudinally of said drum and to follow said resistance wire in continuous contact therewith to include more or less of the resistance wire in the circuit controlled by the rheostat.
19. A rheostat of the class described, comprising a stationary drum, provided on its outer cylindrical surface with a helical groove, a resistance wire tautly wound around said drum and disposed in said
- groove, a shaft journaled for rotation concentrically of the axis of said stationary drum, and a contact device carried by said shaft, said contact device being adapted to move around in said groove and longitudinally of said drum and to follow said resistance wire in continuous contact therewith to include more or less of the resistance wire in the circuit controlled by the rheostat. 50
20. A rheostat of the class described, comprising a stationary drum provided with a cylindrical surface having a helical groove therein, a resistance wire wound in said helical groove, a shaft journaled for rotation substantially concentrically of the axis of said stationary drum, and a contact device carried by said shaft, the end of said contact device being adapted to move around in said groove and longitudinally of said drum and to follow said resistance wire in continuous contact therewith to include more or less of the resistance wire in the circuit controlled by the rheostat. 55
21. A rheostat of the class described, comprising a stationary drum provided with a cylindrical surface having a helical groove therein, high resistance conducting means disposed in said helical groove, a shaft journaled for rotation substantially concentrically of the axis of said cylindrical surface, and a contact device carried by said shaft, the end of said contact device being adapted to move around in said groove and longitudinally of said drum and to follow said 70 high resistance conducting means in continuous contact therewith to include more or less of the high resistance conducting means in the circuit controlled by the said rheostat.
- In witness whereof, I hereunto subscribe 80 my name this 11th day of March, A. D. 1922.
- JOHN ELLIOTT JENKINS.
